CLAIM

The ornamental design for a beverage float, as shown and described.

DESCRIPTION

FIG. 1 is a perspective view of a beverage float showing my new design in its environment;

FIG. 2 is a bottom perspective view thereof;

FIG. 3 is a side elevational view thereof, all sides being identical;

FIG. 4 is a top plan view thereof; and,

FIG. 5 is a bottom plan view thereof.

The broken lines in the drawing are used to illustrate the environment of the beverage float and form no part of the claimed design.
